[57] CLAIM

The ornamental design for a shoe outsole, as shown and described.

DESCRIPTION

FIG. 1 is a bottom plan view of a shoe outsole, showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a left side perspective view thereof; and,

FIG. 7 is a right side perspective view thereof.

The broken line showing of a shoe upper in FIGS. 1-7 is for illustrative purposes only and forms no part of claimed design.
